CLAIM

The ornamental design for drinkware, as shown and described.

DESCRIPTION

FIG. 1 is a top perspective view of a first embodiment of drinkware showing our new design;

FIG. 2 is a front elevation view thereof;

FIG. 3 is a rear elevation view thereof;

FIG. 4 is a right side elevation thereof;

FIG. 5 is a left side elevation view thereof;

FIG. 6 is a top plan view thereof;

FIG. 7 is a bottom plan view thereof;

FIG. 8 is a cross-sectional view thereof taken along 8-8 of FIG. 6;

FIG. 9 is a bottom perspective view thereof with the exemplary base removed to show details not visible in other figures;

FIG. 10 is a top perspective view of a second embodiment of drinkware, showing our new design;

FIG. 11 is a front elevation view thereof;

FIG. 12 is a rear elevation view thereof;

FIG. 13 is a right side elevation thereof;

FIG. 14 is a left side elevation view thereof;

FIG. 15 is a top plan view thereof;

FIG. 16 is a bottom plan view thereof;

FIG. 17 is a cross-sectional view thereof taken along 17-17 of FIG. 15; and,

FIG. 18 is a bottom perspective view thereof with the exemplary base removed to show details not visible in other figures.

The broken lines in the figures depict portions of the drinkware that form no part of the claimed design.

1 Claim, 14 Drawing Sheets
